(57) **CLAIM**

The ornamental design for the gear unit, as shown and described.

DESCRIPTION

FIG. 1 is a front perspective view of the gear unit embodying my new design;

FIG. 2 is a front view thereof;

FIG. 3 is a back view thereof;

FIG. 4 is a right view thereof;

FIG. 5 is a left view thereof;

FIG. 6 is a bottom view thereof; and,

FIG. 7 is a top view thereof.

Broken lines represent unclaimed boundaries of the design. Shading lines are for illustrative purposes only and form no part of the claimed design.
